UNITED STATES PATENT OFFICE.

ROBERT J. SOVEREIGN, OF NEW YORK, N. Y.

COMBUSTION APPARATUS.

Application filed November 13, 1925. Serial No. 68,788.

The invention relates to improvements in air super-heating apparatus for use in connection with fuel burning devices of divers types such as furnaces, boilers, stoves and other heat producing units and has particular reference to an air super-heating means mounted in the feed door of such heat producing structures adapted to project the air induction through various media for pre-heating the cool drafts to direct and deflect same over the entire area of the combustion chamber of the fire-box of such unit to produce live combustible gases for increasing the heat production of the fuel utilized and of the material saving in the quantities of fuel consumed.

The object of the invention resides in the providing of separable and attachable air combustion producing means consisting of an air super-heating unit supported in the fire box door and so disposed within the combustion chamber thereof as extend over the coal bed of said fire box a pre-determined distance to be within the zone of the combustion area of the gases generated by the fuel fire and so placed as to accumulate an increased amount of heat to pre-heat the influx of air from atmosphere to form a gas, and to project such pre-heated air gases directly into the combustion chamber of the heating unit in the form of highly charged gaseous molecules to increase the heat volume of the fuel, to thusly increase the distributive functioning of the heating-unit, to decrease the quantity of fuel consumption and to greatly enhance the efficiency of the generating source.

Another and further object of the invention is in the providing of a pre-heating and gas forming structure constructed along pre-defined lines in such form and design as to increase the air reception and pre-heating chamber, having mounted therein an auxiliary super-heating means, and surface heating area in form of heat absorbing means, and a plurality of apertures so disposed with relation to the emitting end of the unit as to provide means for projecting the semi-gases and pre-heated air to be deflected in spray formation across the entire area of the combustion chamber of the heater and within the prescribed zone therein to assist and create proper combustion, in connection with any of the generally known types and forms of heating structures.

In the following there is described the

general embodiment of the invention the particular features being more particularly pointed hereinafter in the claims.

In the drawings Fig. 1 is a horizontal sectional view of a general type of heat producing furnace provided with the usual form of fire door, and feed aperture, having mounted in said door the combustion gas producing head, and the relative position thereof with the fuel bed of said furnace or heater; Fig. 2 is a face elevation of a heater fire door, and of the position therein of the combustion head air valve, together with a means of controlling said valve by means of either a mechanically or electrically actuated thermostat to regulate the supply of air to said head; Fig. 3 is a longitudinal sectional view of the pre-heating combustion head illustrating the connective features of the air valve, the heat absorbing surface thereto and the means of primarily generating pre-gases and of the means of spraying the heated air directly to the combustion chamber of the heater; Fig. 4 is an end elevation of the spraying head showing the position therein of the air spray apertures and of the disposition thereon of the heat absorbing fins to increase the heating surface of said head; and Fig. 5 is a cross sectional view of said head on the line 5—5 of Fig. 3 illustrating the position therein of the baffle plate to separate the ingress of air to break same up during pre-heating and the deflection of same to the spray head of the burnrite projection.

In the drawings forming part of this application similar numerals of reference indicate similar parts throughout the several views.

In the drawing 1 designates furnace walls and 2 the fire-box thereof above the usual grates to support the fire bed, the area within said walls 1 and above said fire bed comprising the combustion chamber 3, the face plate or wall 4 of said furnace or heater being provided with feed aperture 5 and fire door 6.

Fire door 6 has cut therein an aperture 7 threaded internally to receive pipe connections or nipple 8, the latter thereof being held into position therein by means of lock nut 9, the outer end thereof having mounted thereon an air valve casing 10 of conical or bell shape formation to form an air intake chamber 11. Said valve casing 10 has formed therewith at its outer mouth portion a web 12

provided with a threaded aperture 13 to receive pivotal screw of pin 14 supporting a circular winged damper air valve control 15 consisting of a rotatable flanged member 16 provided with air intake apertures 17 and bat-plate 18 arranged for the regulation of air from atmosphere to the inner confines of the pre-heating gas producing head within the heat generating structure.

10 Pipe connection or nipple 8 may be of any desired length and may be disposed to project within fire box 2 to a point of desired utility, and is externally threaded at 19 to receive the threaded bore 20 of the air pre-heating combustion head 21. Said head 21 is of a pre-determined shape and form tapering outwardly from the heel portion 22 to a point 23 to increase the internal heat capacity, thence tapering toward its front 20 end semi-conically to form an ejector nozzle end 24, the central portion thereof being provided with a bore 25 and plug 26, the object whereof is to provide means whereby one or more combustion heads may be hooked up in 25 unit formation to increase the air pre-heating apparatus for larger sized and increased capacity heat generating equipment.

Head 21 in cross section is square in form and at point 23 has cast therewith a baffle plate 27. The casing 28 on all four surfaces thereof and extending from the heel 22 to the ejector end 24 has formed therewith a plurality of fins 29 the object of which are to provide means adapted to increase the 30 heat retaining and heat producing surface of the said combustion head 21. By constructing the head 21 with the fins as described the heating surface of the same is increased four times in excess of what an ordinary smooth and un-interrupted surface heating head would be provided with and thereby provide a structure having increased efficiency as a combustion unit.

Head 21 has formed internally thereof a primary heating chamber 30 and a secondary heating chamber 31 partitioned partly by baffle plate 27, the open sides thereof producing passageways 32 for the circulation and breaking up of the pre-heated air, and said chamber 30 has mounted therein a quantity of hand formed and packed steel or copper wire 33 to act as baffling means and additional surface heating means for the air in its passage therethrough.

It will be noted that substantially the entire combustion attachment is in form an air pre-heating and superheating means and that the air in passing therethrough from atmosphere, will in reaching the primary and secondary heating chambers 30 and 31 become semi-gaseous and be combustible before it is projected through the series of apertures 34 in the form of a spray, to the combustion chamber 2. Said apertures 34 are disposed 60 across the face of the head 21 in line and

offset position in order to provide means whereby the pre-heated air and semi-gaseous air is ejected in arc-like form across the entire fire box at a point of the proper mixture of the air and gases within said chamber to 70 form a complete combustion and using up of all of the heat producing media of the fuel used, with the result that decreased coal consumption is assured, increased heat production is assured, and increased efficiency of the 75 equipment employed is the result.

Further means may form part of the invention in the providing of the control of air valve 11 and dampers with a bell crank 80 35 operative through switch or escapement control 36 and actuated by thermostat 37, for opening and closing the air regulator to increase or decrease the heat producing facilities of the furnace or other heat generating structure to which the apparatus as 85 is herein shown and described may be applied.

It is obvious that the structure making up the invention herein may be varied in many ways without departing from the spirit of 90 the same and without limiting the scope of the disclosures herewith defined.

What is claimed and desired to secure by Letters Patent of the United States is:

1. A device of the character described, comprising a combustion means for furnaces and the like, including a member mounted in the fire door of such furnace, an air valve, a pipe mounted in said fire door arranged to connect said combustion means with said air valve, said combustion means being of hollow unitary structure in double frusto pyramidal form having their bases joined and a baffle extending across the hollow space at said juncture and having formed therewith and extending longitudinally thereof a plurality of super-heating fins, a plurality of apertures cut in the walls of said combustion means on one of said frusto pyramidal ends of said combustion means 100 adjacent said fins and disposed at an angle to the axis of said combustion means arranged to project the air over and within the fire box of said furnace, and an air pre-heating conductive baffle packing composed of coiled wire adapted to assist in pre-heating the air passing through said combustion means.

2. A device of the character described, including an air super-heating combustion head for heat-producing units comprising a unitary structure in double frusto pyramidal form having their bases joined and a baffle extending across the hollow space at said juncture, an air valve, a pipe mounted in the fire door of said heat-producing units supporting said air valve and said combustion head, a plurality of fins arranged for super-heating the walls of said combustion head and formed with the cas- 120 110 115 130

ing of said combustion head, a steel wire and wool conductive baffle packing mounted in one of the chambers of said combustion head, said combustion head having formed therein two chambers by reason of the baffle at the juncture of the bases of said double frusto pyramidal structure, said steel wire and wool conductive baffle packing being arranged to pre-heat the air passing there-
10 through, a plurality of apertures cut in the walls of one of the pyramidal ends of said unitary form of combustion head, part of said apertures being disposed at an angle

to the axis of said combustion head for dif-
fusing the super-heated air over and within
the fire box of said heat-producing units,
and means formed in the outer end of said
combustion head arranged to receive a con-
nection to which a like combustion head may
be attached to increase the combustion means
for heat-producing units.

In testimony whereof I have signed my
name to this specification this 24th day of
August, 1925.

ROBERT J. SOVEREIGN.
